UNITED STATES PATENT OFFICE.

JOSEPH YANCEY CLARK, OF WINNIPEG, MANITOBA, CANADA.

MACHINE FOR PRODUCING MULTIPLE POWER.

1,122,687.

Specification of Letters Patent. Patented Dec. 29, 1914.

Application filed June 7, 1913. Serial No. 772,391.

To all whom it may concern:

Be it known that I, JOSEPH YANCEY CLARK, of the city of Winnipeg, in the Province of Manitoba, Canada, have invented certain new and useful Improvements in Machines for Producing Multiple Power, of which the following is the specification.

The object of the invention is to provide a durable, efficient and inexpensive machine whereby potential energy can be utilized for driving purpose, the arrangement being such that the machine is entirely automatic, releasing and storing the potential energy in such a manner that at all times during the operation of the machine a large power is available for driving or other such purposes.

With the above objects in view the invention consists essentially in a plurality of similarly constructed elements capable of storing up and releasing potential energy, said elements being connected to and carried by a rotatably mounted shaft, means for successively storing up potential energy in the respective elements, means for automatically releasing successively the potential energy so stored and in so doing rotating the shaft carrying the elements, and means whereby the action of the elements on the shaft can be controlled to permit any desired number of them to be put in operation, the parts being arranged and constructed as hereinafter more particularly described, and later pointed out in the appended claims.

Referring to the drawings,—Figure 1 represents a side view of my complete machine. Fig. 2 represents a vertical sectional view through the machine, the section being taken in the plane denoted by the line X—X'. Fig. 1. Fig. 3 represents an enlarged detailed vertical sectional view through one of the clutches employed, the shaft carrying the clutches being shown in side elevation. Fig. 4 represents an enlarged detailed vertical sectional view through the shaft carrying one of the controlling arms, the arm being shown in side elevation. Fig. 5 represents an enlarged detailed vertical sectional view through one of the springs employed and adjoining parts. Fig. 6 is an enlarged detailed perspective view showing one of the trip devices for engaging and disengaging one of

the clutches. Fig. 7 is an enlarged perspective view of the bearings carrying one of the springs. Fig. 8 represents an enlarged sectional view through the top shaft at Y—Y' showing the controlling levers in side elevation. Fig. 9 is an enlarged detailed perspective view of a portion of one of the bell cranks and adjoining parts.

In the drawing like characters of reference indicate corresponding parts in each figure.

1, 2, 3, 4, 5 and 6 represent similar standards, all provided with cross members 7 and upright members 8, the said standards being suitably spaced apart and aligned and fastened permanently by bolts 9 to a supporting base 10.

11 represents a lower shaft rotatably mounted in suitable bearings 12 carried by the standards. The shaft is fitted at the ends with fly-wheels 13 and 14, the latter carrying a pulley 15 connected through a belt 16 with a pulley 17 located on the drive shaft 18 of an electric motor 19. The motor is shown as one of the many forms of driving means which could be utilized for rotating the shaft 11.

On the shaft 11 and between the standards I have placed friction clutches 20, 21, 22, 23 and 24, which comprise in each instance the following parts:—A rotatably mounted female clutch member 25 and a slidably mounted male clutch member 26, the male clutch member having a beveled edge designed upon said male clutch member being shifted to make frictional contact with the female clutch member, the inner face of which is beveled out to receive it. The female clutch members as before stated are mounted freely on the shaft and carry integral drums 27, 28, 29, 30 and 31, the drums and clutch members being prevented from end displacement on the shaft by collars 32 and 33 fastened in any suitable way to the shaft.

The male clutch members 26 are held by feathers 34 so that they rotate with the shaft although they are free to slide endwise on the shaft. Each male clutch member is coupled to a shiftable sleeve 35 in such a manner that the male clutch member is compelled to shift endwise with the sleeve but can rotate independent of the sleeve. A spiral spring 36 is mounted between each of the sleeves and the adjoining bearing 12,

the tendency of the spring in each instance being to engage the clutch members.

37, 38, 39, 40 and 41 are clutch controlling bell cranks pivotally secured by pins 42 to the respective standards. Each bell crank has a vertically and horizontally disposed portion, the horizontally disposed portion passing more or less directly over the clutch for a purpose later explained, while the vertically disposed portion passes downwardly and spans the sleeve 35 adjoining each male clutch member. Pins 43 fasten these vertically disposed portions of the bell cranks pivotally to the sleeves.

15 44 is a hollow top or upper shaft parallel with the bottom shaft and suitably mounted in similar bearings 45 permanently secured to the standards 1, 2, 3, 4, 5 and 6 respectively. This shaft is supplied at one end 20 with a pulley 46 and at the other end with a collar 47, the collar rotating with the shaft and being supplied with a number of extending lugs, to which I have secured pivotally controlling levers 48, 49, 50, 51 and 25 52, the purpose of these being explained hereinafter. 53 are similar hollow extension bearings permanently secured by bolts to the faces of the bearings 45 and receiving the shaft 44 freely.

30 54, 55, 56, 57 and 58 are coiled flat springs mounted on the bearing 53 and having their inner ends in each instance fastened to the bearings by lugs 59 cast on the bearings, the lugs protruding through suitable openings 35 formed in the springs.

60, 61, 62, 63 and 64 are grooved wheels rotatably mounted on the shaft 44 and adjoining the bearings 53. These wheels are prevented against end displacement in one 40 direction by having the hubs 65 thereof butting against the bearings 53 and are further prevented from end displacement in the opposite direction, that is in a direction away from the bearings by collars 66 shrunk 45 on the shaft. The outer ends of the flat coil springs are secured permanently to the respective grooved wheels by pins 67. In this way the wheels are virtually tied through the springs and bearings 53 and 45 to the 50 standards. The ends of the hubs 65 farthest from the bearings 53 are fitted with ratchet teeth 68 which teeth are normally engaged by complementary ratchet teeth 69 provided on the adjoining ends of sleeves 55 70 slidably mounted on the upper shaft and compelled to rotate with the same through the action of feathers 71.

72 are collars fixed on the top shaft at a short distance from each of the sleeves 70.

60 73 are spiral springs located on the shaft between the respective sleeves and collars, these springs tending to press the teeth 69 continuously into engagement with the teeth 68.

55 74, 75, 76, 77 and 78 are controlling arms

suitably mounted on pivot pins 79 carried by bearing blocks 79' fixed on the top shaft.

It is here to be noticed (see detail Fig. 4) that each controlling arm is supplied with a projecting lip 79² which is designed to engage with the bearing block and prevent the controlling arm from being swung in a left hand direction farther than the upright position, the upright position being considered as at right angles to the shaft.

Wires, cables or such like 80 connect the respective controlling arms with the respective controlling levers, these wires passing through the hollow center of the shaft 44. A spiral spring 81 is placed on each wire 80 between the controlling arm and the shaft and holds the arm normally in an upright position and in so doing also holds the controlling lever in each case in an upright position radiating from the shaft. By this arrangement it will be seen that one can select and swing one or other of the controlling arms toward the shaft by grasping the corresponding lever and pulling it in the direction indicated by the arrow "a" Fig. 1.

Assuming that the machine is running and that all the levers are in a position as shown in Fig. 1 of the drawings, i. e., standing in a position at right angles to the shaft, and that it is desired to cut out the action 95 of any one of the springs 73 on the shaft 44 through ratchet teeth, it would only be necessary to select the lever corresponding to the controlling arm adjoining the spring selected and swing the lever downwardly to 100 a position more or less aligned with the shaft. This action would cause the cable to pull the controlling arm over so it would miss hitting, in the rotation of the shaft 44, the upper end of the square actuating shaft. 105 The result would be that the particular trip mechanism selected would not be set off and accordingly by the pulley controlled by said trip mechanism would not be freed to rotate. As a result, the associated spring 110 410 would not be released. It is to be borne in mind that although there is a spring 81 on each cable tending to face the controlling arm up, still this action is counteracted by the position which the lever occupies when 115 swung down, as enlarged upon in the following paragraph of the specification. These levers permit any of the springs to be thrown in or out.

The controlling levers are fitted in a 120 manner such that when they are swung down to a position more or less parallel with the shaft they become locked and remain in the swung down position, in other words, the wire connected to the lever is 125 passed to a position below the pivot point of the said lever when the said lever is swung down.

It is here to be noticed that the controlling arms are arranged in different posi- 130

tions, each one in the present instance being located one fifth of a revolution in advance of the other.

The bearings 45 provide an extending arm 582 having an offset end 82' the extremity of which is more or less directly above the extending ends of the horizontally disposed positions of the bell cranks 37, 38, 39, 40 and 41 in each instance. The offset ends of 10 these arms form upper bearings for trip devices 83, 84, 85, 86 and 87 inserted between the extremities 82' of the arms and the horizontally disposed portions of the bell cranks in each instance, which trip devices are designed to engage or disengage the respective clutch members at predetermined instants depending on the positions of the wheels. These trip devices are now described: Each presents a more or less open 20 rectangular frame 88 formed from side members 88' and 88² and top and bottom members 88³ and 88⁴, the side members 88' extending upwardly considerably beyond the frame and being received slidably in the 25 offset end 82' of the adjoining arm 82. The upper end of the side member 88' above the arm is offset to form a trip 89, the purpose of which will be later apparent. A guide bar 90 extends downwardly from the cross 30 members 88² of the frame and is received slidably in the end of the horizontally disposed portion of the adjoining bell crank. The top member 88³ of the frame extends 35 beyond the upright portion 88² of the frame and forms a trip the purpose of which will be later explained.

It is here to be noticed that the upright member 88² of the frame is notched away at the top at 88⁵ on the one side and has the 40 opposite side presenting a curved enlargement 88⁶ which is received between the guides 91' of a bar 91 having the body portion thereof supplied with a catch piece 91² normally enlarged with the end of the horizontally disposed portion of the adjoining bell crank in each instance. Each bar 91 is supported by a flat spring 92 fastened 45 permanently to the adjoining standard.

The grooved wheels carry each an extending pin 93 arranged when the wheels are rotated in a clockwise direction to engage with the under sides of the top members 88⁴ of the respective trip devices and raise them and when rotated in a counter-clockwise direction to engage with the trips 55 89 of the respective trip devices and depress them.

When any one of the trip devices is raised in the manner just described the catch piece 60 91² is released from the end of the bell crank by the action of the curved portion 88 of the member 88², which forces the bar 91 toward the adjoining standard or away 65 from the end of the bell crank. Immediately the bell crank is released the spring

36 operates to throw the female clutch member 26 into engagement with the male clutch member 24.

When any one of the trip devices is lowered or forced down in the manner above referred to it carries the horizontally disposed portion of the bell crank down with it until the bell crank is again locked by the catch piece 91², the clutch members accordingly being disengaged.

94 are brakes located above the male clutch member and carried by bars 94' permanently secured to the respective bell cranks. These brakes engage and disengage with the faces of the male clutch members depending on the positions of the bell cranks.

95 are cables secured to the grooved wheels and also to the drums. The cables wind off the drums onto the pulleys or vice-versa when the machine is operating. The brakes are supplied to prevent drums from spinning on the shaft when the male clutch members are disengaged.

96 are cross bars carrying the respective 20 uprights 8 of the standards 7, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 580, 581, 582, 583, 584, 585, 586, 587, 588, 589, 590, 591, 592, 593, 594, 595, 596, 597, 598, 599, 600, 601, 602, 603, 604, 605, 606, 607, 608, 609, 610, 611, 612, 613, 614, 615, 616, 617, 618, 619, 620, 621, 622, 623, 624, 625, 626, 627, 628, 629, 630, 631, 632, 633, 634, 635, 636, 637, 638, 639, 640, 641, 642, 643, 644, 645, 646, 647, 648, 649, 650, 651, 652, 653, 654, 655, 656, 657, 658, 659, 660, 661, 662, 663, 664, 665, 666, 667, 668, 669, 670, 671, 672, 673, 674, 675, 676, 677, 678, 679, 680, 681, 682, 683, 684, 685, 686, 687, 688, 689, 690, 691, 692, 693, 694, 695, 696, 697, 698, 699, 700, 701, 702, 703, 704, 705, 706, 707, 708, 709, 710, 711, 712, 713, 714, 715, 716, 717, 718, 719, 720, 721, 722, 723, 724, 725, 726, 727, 728, 729, 730, 731, 732, 733, 734, 735, 736, 737, 738, 739, 740, 741, 742, 743, 744, 745, 746, 747, 748, 749, 750, 751, 752, 753, 754, 755, 756, 757, 758, 759, 750, 751, 752, 753, 754, 755, 756, 757, 758, 759, 760, 761, 762, 763, 764, 765, 766, 767, 768, 769, 770, 771, 772, 773, 774, 775, 776, 777, 778, 779, 770, 771, 772, 773, 774, 775, 776, 777, 778, 779, 780, 781, 782, 783, 784, 785, 786, 787, 788, 789, 780, 781, 782, 783, 784, 785, 786, 787, 788, 789, 790, 791, 792, 793, 794, 795, 796, 797, 798, 799, 790, 791, 792, 793, 794, 795, 796, 797, 798, 799, 800, 801, 802, 803, 804, 805, 806, 807, 808, 809, 800, 801, 802, 803, 804, 805, 806, 807, 808, 809, 810, 811, 812, 813, 814, 815, 816, 817, 818, 819, 810, 811, 812, 813, 814, 815, 816, 817, 818, 819, 820, 821, 822, 823, 824, 825, 826, 827, 828, 829, 820, 821, 822, 823, 824, 825, 826, 827, 828, 829, 830, 831, 832, 833, 834, 835, 836, 837, 838, 839, 830, 831, 832, 833, 834, 835, 836, 837, 838, 839, 840, 841, 842, 843, 844, 845, 846, 847, 848, 849, 840, 841, 842, 843, 844, 845, 846, 847, 848, 849, 850, 851, 852, 853, 854, 855, 856, 857, 858, 859, 850, 851, 852, 853, 854, 855, 856, 857, 858, 859, 860, 861, 862, 863, 864, 865, 866, 867, 868, 869, 860, 861, 862, 863, 864, 865, 866, 867, 868, 869, 870, 871, 872, 873, 874, 875, 876, 877, 878, 879, 870, 871, 872, 873, 874, 875, 876, 877, 878, 879, 880, 881, 882, 883, 884, 885, 886, 887, 888, 889, 880, 881, 882, 883, 884, 885, 886, 887, 888, 889, 890, 891, 892, 893, 894, 895, 896, 897, 898, 899, 890, 891, 892, 893, 894, 895, 896, 897, 898, 899, 900, 901, 902, 903, 904, 905, 906, 907, 908, 909, 900, 901, 902, 903, 904, 905, 906, 907, 908, 909, 910, 911, 912, 913, 914, 915, 916, 917, 918, 919, 910, 911, 912, 913, 914, 915, 916, 917, 918, 919, 920, 921, 922, 923, 924, 925, 926, 927, 928, 929, 920, 921, 922, 923, 924, 925, 926, 927, 928, 929, 930, 931, 932, 933, 934, 935, 936, 937, 938, 939, 930, 931, 932, 933, 934, 935, 936, 937, 938, 939, 940, 941, 942, 943, 944, 945, 946, 947, 948, 949, 940, 941, 942, 943, 944, 945, 946, 947, 948, 949, 950, 951, 952, 953, 954, 955, 956, 957, 958, 959, 950, 951, 952, 953, 954, 955, 956, 957, 958, 959, 960, 961, 962, 963, 964, 965, 966, 967, 968, 969, 960, 961, 962, 963, 964, 965, 966, 967, 968, 969, 970, 971, 972, 973, 974, 975, 976, 977, 978, 979, 970, 971, 972, 973, 974, 975, 976, 977, 978, 979, 980, 981, 982, 983, 984, 985, 986, 987, 988, 989, 980, 981, 982, 983, 984, 985, 986, 987, 988, 989, 990, 991, 992, 993, 994, 995, 996, 997, 998, 999, 990, 991, 992, 993, 994, 995, 996, 997, 998, 999, 1000, 1001, 1002, 1003, 1004, 1005, 1006, 1007, 1008, 1009, 1000, 1001, 1002, 1003, 1004, 1005, 1006, 1007, 1008, 1009, 1010, 1011, 1012, 1013, 1014, 1015, 1016, 1017, 1018, 1019, 1010, 1011, 1012, 1013, 1014, 1015, 1016, 1017, 1018, 1019, 1020, 1021, 1022, 1023, 1024, 1025, 1026, 1027, 1028, 1029, 1020, 1021, 1022, 1023, 1024, 1025, 1026, 1027, 1028, 1029, 1030, 1031, 1032, 1033, 1034, 1035, 1036, 1037, 1038, 1039, 1030, 1031, 1032, 1033, 1034, 1035, 1036, 1037, 1038, 1039, 1040, 1041, 1042, 1043, 1044, 1045, 1046, 1047, 1048, 1049, 1040, 1041, 1042, 1043, 1044, 1045, 1046, 1047, 1048, 1049, 1050, 1051, 1052, 1053, 1054, 1055, 1056, 1057, 1058, 1059, 1050, 1051, 1052, 1053, 1054, 1055, 1056, 1057, 1058, 1059, 1060, 1061, 1062, 1063, 1064, 1065, 1066, 1067, 1068, 1069, 1060, 1061, 1062, 1063, 1064, 1065, 1066, 1067, 1068, 1069, 1070, 1071, 1072, 1073, 1074, 1075, 1076, 1077, 1078, 1079, 1070, 1071, 1072, 1073, 1074, 1075, 1076, 1077, 1078, 1079, 1080, 1081, 1082, 1083, 1084, 1085, 1086, 1087, 1088, 1089, 1080, 1081, 1082, 1083, 1084, 1085, 1086, 1087, 1088, 1089, 1090, 1091, 1092, 1093, 1094, 1095, 1096, 1097, 1098, 1099, 1090, 1091, 1092, 1093, 1094, 1095, 1096, 1097, 1098, 1099, 1100, 1101, 1102, 1103, 1104, 1105, 1106, 1107, 1108, 1109, 1100, 1101, 1102, 1103, 1104, 1105, 1106, 1107, 1108, 1109, 1110, 1111, 1112, 1113, 1114, 1115, 1116, 1117, 1118, 1119, 1110, 1111, 1112, 1113, 1114, 1115, 1116, 1117, 1118, 1119, 1120, 1121, 1122, 1123, 1124, 1125, 1126, 1127, 1128, 1129, 1120, 1121, 1122, 1123, 1124, 1125, 1126, 1127, 1128, 1129, 1130, 1131, 1132, 1133, 1134, 1135, 1136, 1137, 1138, 1139, 1130, 1131, 1132, 1133, 1134, 1135, 1136, 1137, 1138, 1139, 1140, 1141, 1142, 1143, 1144, 1145, 1146, 1147, 1148, 1149, 1140, 1141, 1142, 1143, 1144, 1145, 1146, 1147, 1148, 1149, 1150, 1151, 1152, 1153, 1154, 1155, 1156, 1157, 1158, 1159, 1150, 1151, 1152, 1153, 1154, 1155, 1156, 1157, 1158, 1159, 1160, 1161, 1162, 1163, 1164, 1165, 1166, 1167, 1168, 1169, 1160, 1161, 1162, 1163, 1164, 1165, 1166, 1167, 1168, 1169, 1170, 1171, 1172, 1173, 1174, 1175, 1176, 1177, 1178, 1179, 1170, 1171, 1172, 1173, 1174, 1175, 1176, 1177, 1178, 1179, 1180, 1181, 1182, 1183, 1184, 1185, 1186, 1187, 1188, 1189, 1180, 1181, 1182, 1183, 1184, 1185, 1186, 1187, 1188, 1189, 1190, 1191, 1192, 1193, 1194, 1195, 1196, 1197, 1198, 1199, 1190, 1191, 1192, 1193, 1194, 1195, 1196, 1197, 1198, 1199, 1200, 1201, 1202, 1203, 1204, 1205, 1206, 1207, 1208, 1209, 1200, 1201, 1202, 1203, 1204, 1205, 1206, 1207, 1208, 1209, 1210, 1211, 1212, 1213, 1214, 1215, 1216, 1217, 1218, 1219, 1210, 1211, 1212, 1213, 1214, 1215, 1216, 1217, 1218, 1219, 1220, 1221, 1222, 1223, 1224, 1225, 1226, 1227, 1228, 1229, 1220, 1221, 1222, 1223, 1224, 1225, 1226, 1227, 1228, 1229, 1230, 1231, 1232, 1233, 1234, 1235, 1236, 1237, 1238, 1239, 1230, 1231, 1232, 1233, 1234, 1235, 1236, 1237, 1238, 1239, 1240, 1241, 1242, 1243, 1244, 1245, 1246, 1247, 1248, 1249, 1240, 1241, 1242, 1243, 1244, 1245, 1246, 1247, 1248, 1249, 1250, 1251, 1252, 1253, 1254, 1255, 1256, 1257, 1258, 1259, 1250, 1251, 1252, 1253, 1254, 1255, 1256, 1257, 1258, 1259, 1260, 1261, 1262, 1263, 1264, 1265, 1266, 1267, 1268, 1269, 1260, 1261, 1262, 1263, 1264, 1265, 1266, 1267, 1268, 1269, 1270, 1271, 1272, 1273, 1274, 1275, 1276, 1277, 1278, 1279, 1270, 1271, 1272, 1273, 1274, 1275, 1276, 1277, 1278, 1279, 1280, 1281, 1282, 1283, 1284, 1285, 1286, 1287, 1288, 1289, 1280, 1281, 1282, 1283, 1284, 1285, 1286, 1287, 1288, 1289, 1290, 1291, 1292, 1293, 1294, 1295, 1296, 1297, 1298, 1299, 1290, 1291, 1292, 1293, 1294, 1295, 1296, 1297, 1298, 1299, 1300, 1301, 1302, 1303, 1304, 1305, 1306, 1307, 1308, 1309, 1300, 1301, 1302, 1303, 1304, 1305, 1306, 1307, 1308, 1309, 1310, 1311, 1312, 1313, 1314, 1315, 1316, 1317, 1318, 1319, 1310, 1311, 1312, 1313, 1314, 1315, 1316, 1317, 1318, 1319, 1320, 1321, 1322, 1323, 1324, 1325, 1326, 1327, 1328, 1329, 1320, 1321, 1322, 1323, 1324, 1325, 1326, 1327, 1328, 1329, 1330, 1331, 1332, 1333, 1334, 1335

suming that the springs are wound, that is, that the clutches are all out, this position of the parts being shown in Fig. 1 of the drawings.

- 3 The winding of the springs can be accomplished primarily in any way such as by hand, by turning the grooved wheels in a clockwise direction. In the present instance one then has the potential energy 10 of five springs stored up to do work on the shaft 44 immediately said wheels are released by withdrawing the latches. The springs are controlled by the trip device in such a way that only one of them is 15 being wound at a time, the winding being done by the shaft 11 which is rotated by the motor. A small motor will be effective for this purpose as will readily be understood. To start the machine so that it can 20 be utilized for delivering a considerable power from the pulley 46, the motor having been previously started and the shaft 11 consequently rotating, the attendant has simply to depress the first actuating shaft 25 97 to withdraw the adjoining latch 104 and release the arm 107 of the wheel 60. The said wheel immediately rotates owing to the action of the spring and in rotating turns the shaft 44, the controlling arm 74 30 passing the upper end of the shaft 97 held down by the attendant. As the shaft 44 continues rotating, the actuating arms 75, 76, 77 and 78 successively engage with the shafts 98, 99, 100, and 101 and release successively the several arms 107 of the 35 respective wheels 61, 62, 63, and 64. Accordingly the potential energies stored in the springs are successively released to operate on and rotate the shaft 44.
- 40 The trip mechanisms are designed so that very shortly after the five springs have been released the pin 93 of the first wheel 60 engages with the under side of the top member 88⁴ of the trip device 83 and raises the trip device with the result that the bell crank 37 is released and the clutch 20 is engaged. This occurs also about the time that the first spring is unwound. Immediately the clutch 20 is engaged the shaft 11 45 carries with it the drum 27, the cable winding on the drum and pulling the wheel 60 in a clockwise direction thereby rewinding the attached spring. The said wheel is then held against rotation by the latch 104. During 50 the rewinding operation of the first spring the remaining four springs are operating to rotate the shaft. Almost immediately after the first spring is wound the second spring which is at this time almost unwound 55 is rewound, its clutch 21 being engaged by the pin 93 actuating the trip device 84. Immediately before the clutch members of the clutch 21 are engaged the first controlling arm engages the shaft 102 and sets off, so 60 to speak, the first spring. This operation

continues as long as the machine is to be used, one of the springs being rewound at a time. According to the arrangement I have five of the springs acting on the shaft to rotate the same for a short time and four 70 at all other times during one rotation of the shaft 44.

In an actual machine the shaft 11 rotates at a comparatively high speed relative to the shaft 44. I may say that as an example in a machine which I have built wherein five elements such as those shown in the drawings are used the shaft 11 rotates sixty-four revolutions to one revolution of the shaft 44. In this machine it takes approximately 80 eight revolutions of the shaft 11 to wind one of the springs. Accordingly it will be seen that in forty revolutions of the shaft 11 all the springs will be wound and the shaft 44 will not have at this time rotated a complete 85 revolution. During the short time which it takes the top shaft to complete this revolution I have five of the springs operating to rotate the shaft 44 and during the other portion of the revolution of the said shaft I 90 have four springs operating to rotate the same.

It will of course be apparent that the springs are wound very quickly owing to the high speed of the shaft 11. A machine constructed in accordance with my invention therefore allows me to have a comparatively 95 powerful drive at the pulley 46 with but a small motor employed for rotating the shaft 11 and controlling the winding and releasing 100 of the springs in their proper order.

The machine is stopped by throwing down the controlling levers 43 which action causes the controlling arm 74 to swing toward the shaft 44 and pass out of the paths of the 105 actuating shafts. The top shaft will continue to rotate owing to the action of the springs, each spring in succession uncoiling and then being rewound, the pins 93 successively engaging the successive trip devices 110 and engaging the clutches, which clutches are afterward thrown out by the pins again engaging with the trip 89 of the respective trip devices. Once however the respective 115 springs are rewound they are not released as the controlling arms are in such a position that they do not engage with the actuating shafts to release the latches. The machine accordingly when stopped is left in such a state that it is unnecessary to wind 120 the springs by hand or otherwise as previously stated. The machine can immediately be started by throwing the controlling levers to a position which will cause the controlling arms to engage with the actuating shafts 125 and then depressing by hand one of the actuating arms to release one of the springs.

I wish to point out that although I have only disclosed five elements, any number of elements can be used to advantage, this de- 130

pending on the power required to be delivered by the pulley 47. I can also increase this power by using stronger springs but in this case a larger motor would be required in order to wind the springs successively.

I do not wish to be limited to any form of trip mechanism for controlling the winding and releasing of the springs of each element as these could be readily modified without departing from the spirit of the invention.

What I claim as my invention is:

1. The combination comprising a rotatably mounted shaft, a plurality of similar spring actuated elements connected with the shaft, means for operating the elements to wind the springs independent of the shafts and so store up potential energy in the springs, means for successively locking the elements upon the springs being wound and means for automatically unlocking successively the elements to free the springs to operate on and rotate the shaft, as and for the purpose specified.

2. The combination comprising a rotatably mounted shaft, a plurality of similar rotatably mounted spring actuated elements connected with the shaft, means for successively rotating the elements to wind the springs independent of the shafts and store up potential energy in the springs, means for locking the elements against rotation upon the springs being wound and thereby retaining and storing the potential energy in the springs, means for automatically and successively unlocking the latter means to free the springs to unwind and means for coupling the elements to the shaft during the unwinding operation of the springs, as and for the purpose specified.

3. The combination comprising a rotatably mounted shaft, a plurality of similar wheels rotatably mounted on the shaft, winding springs each having one end permanently secured to a wheel and the other end fastened to an adjoining permanent structure, means for successively rotating the wheels on the shaft to wind the springs, means for successively locking the wheels against rotation upon the springs being wound, means for automatically and successively unlocking the latter locking means to free the springs to unwind and means for automatically coupling the wheels to the shaft during the unwinding operation of the springs, as and for the purpose specified.

4. The combination comprising a shaft pivotally mounted in suitable supporting standards, a plurality of similar wheels rotatably mounted on the shaft, springs having each one end connected to a wheel and the opposite end connected with the standard, means for successively rotating the wheels on the shaft to wind the respective springs, automatic means for successively locking the wheels against rotation upon the

springs being wound, means for successively releasing the locking means to free the springs to unwind and rotate the wheels and means for coupling the wheels to the shaft during the unwinding operation of the springs, as and for the purpose specified.

5. The combination comprising a plurality of standards, a shaft rotatably mounted in the standards, a plurality of wheels rotatably mounted on the shaft and adjoining the standard, a plurality of extension bearings permanently secured to the standards, a plurality of coiled springs having each an end anchored permanently to a bearing and an end fastened permanently to a wheel, means for automatically and successively rotating the wheels irrespective of the shaft to wind the springs, means for automatically and successively locking the wheels against rotation upon the springs being wound, means for successively releasing the locking means to free the wheels to rotate under the action of the springs and means for automatically coupling the wheels with the shaft during the latter rotation, as and for the purpose specified.

6. The combination comprising a plurality of standards, a top shaft rotatably mounted in the standards, a rotatably mounted lower shaft carried by the standards, means for continuously rotating the lower shaft, a plurality of grooved wheels rotatably mounted on the top shaft, a plurality of extension bearings carried by the standards and adjoining the top shaft, a plurality of coiled flat springs mounted on the bearings and having their lower ends fastened to the bearings and their upper ends secured to the wheels, a plurality of drums rotatably mounted on the bottom shaft, cables connecting the drums with the grooved wheels, clutch members associated with the bottom shaft and the drums and designed when engaged to cause the drums to operate the wheels and wind the springs, a trip mechanism associated with the wheels and the clutches and designed to automatically disengage the clutch members upon the springs being wound, a plurality of similar trip devices designed to lock the wheels against rotation immediately the springs are wound, controlling arms carried by the top shaft and designed to engage with the respective trip mechanisms and release the locking means thereby freeing the wheels successively to rotate under the action of the springs and thereby coupling the wheels with the top shaft during the interval the springs are unwinding, as and for the purpose specified.

7. The combination comprising a plurality of supporting standards, a top shaft rotatably mounted in the standards, a lower shaft rotatably carried by the standards, means for continuously rotating the lower

shaft, extension bearings carried by the standards and adjoining the top shaft, a plurality of similar grooved wheels rotatably mounted on the top shaft and adjoining the extension bearings, coil springs mounted on the bearings and having their inner ends connected thereto and their outer ends fastened to the wheels, a plurality of drums rotatably mounted on the bottom shaft and presenting male clutch members, a plurality of female clutch members feathered on the bottom shaft and engageable with the male clutch members, bell cranks pivotally secured to the standards and connected with the female clutch members, cables connecting the respective drums with the respective wheels, said cables and drums being designed upon the engagement of the clutch members to rotate the wheels and wind the springs irrespective of the top shaft, trip mechanism designed to lock the pulleys against rotation upon the springs being wound, actuating arms carried by the top shaft and designed to successively engage with the trip mechanisms and release the wheels, means automatically coupling the wheels to the top shaft during the intervals that the springs are unwinding, trip devices associated with each of the wheels and the bell cranks and designed to automatically free the clutch members to engage the instant the successive springs are unwound, as and for the purpose specified.

8. The combination comprising a plurality of suitable standards, a top shaft rotatably mounted in the standards, a bottom shaft rotatably carried by the standards, means for continuously rotating the bottom shaft, a plurality of permanent extension 55 bearings carried by the standards and receiving the top shaft, a plurality of grooved wheels rotatably mounted on the top shaft, coiled flat springs mounted on and having their inner ends connected to the bearings and their outer ends fastened to the wheels, a plurality of drums rotatably mounted on the bottom shaft and fitted each with a male clutch member, a plurality of female clutch members slidably mounted on the bottom 60 shaft and designed to engage with the former clutch members, spiral springs engaging with the female clutch members and tending normally to engage the female with the male clutch members, pivotally mounted bell cranks connected with the female clutch members, shiftable trip devices normally engaged with the bell cranks and retaining the clutches normally disengaged, pins extending from the wheels and designed to 65 engage successively with the respective trip devices and free the bell cranks thereby causing the drums to rotate and wind the springs, trip mechanisms designed successively to lock the wheels against rotation upon the springs being wound, controlling

70 arms carried by the top shaft and designed to engage successively with the trip mechanisms and unlock the wheels to rotate under the action of the springs and means for coupling the wheels to the top shaft during the unwinding operation of the springs, as and for the purpose specified.

9. The combination comprising a plurality of standards, a top shaft rotatably mounted in the standards, a lower shaft rotatably carried by the standards, means for continuously rotating the lower shaft, an extension bearing carried by each of the standards and receiving the top shaft, grooved wheels rotatably mounted on the top shaft and having the hubs thereof provided with ratchet teeth, flat coil springs mounted on the bearings having their inner ends secured thereto and their outer ends fastened to the wheels, spring pressed sleeves slidably mounted on the top shaft and provided with ratchet teeth complementary to the former teeth, said teeth being designed to pass each other freely upon the wheels being rotated in a clockwise direction and to engage upon the said wheels being rotated in a counter-clockwise direction, drums rotatably mounted on the bottom shaft and provided each with a male clutch member, female clutch members feathered on the bottom shaft and engageable with the male clutch members, spiral springs associated with the female clutch members and tending normally to engage them with the male clutch members, pivotally mounted bell cranks connected with the female clutch members, a shiftable trip device carried by each of the standards and engaging normally with the bell cranks and retaining the clutch members out of engagement, winding cables connecting the drums with the grooved wheels and designed when wound on the drums to rotate the wheels in a clockwise direction and wind the springs, a pin extending from each of the wheels and designed in the rotation of the wheels to engage with and shift the trip device thereby releasing the associated bell crank, an arm extending from each of the wheels, a suitably supported trip mechanism engageable with each of the arms and designed when engaged to lock the wheels against rotation in a counter-clockwise direction owing to the action of the springs and controlling arms carried by the top shaft and designed when rotated with the said shaft to engage with the trip mechanisms and unlock the arms, as and for the purpose specified.

10. In a machine of the class described 125 the combination with a rotatably mounted hollow shaft, and potential energy storing means on said shaft, of a plurality of pivoted controlling arms extending from the shaft at suitable locations throughout the length 130

thereof, controlling levers located at one end of the shaft and means connecting the respective levers with the respective arms, said means passing through the hollow center of the shaft, and trips engaging said potential energy storing means to prevent the rotation thereof, said controlling arms being adapted to release such trips as and for the purpose specified.

10 11. In a machine of the class described the combination with a rotatably mounted hollow shaft, and potential energy storing means on said shaft, of a plurality of controlling arms pivotally secured to the shaft and located at suitable positions throughout the length thereof, a plurality of controlling levers pivotally secured to one end of the shaft and wires connecting the respective controlling levers with the respective arms, said wires passing through the hollow center of the shaft, and trips engaging said potential energy storing means to prevent the rotation thereof, said controlling arms being adapted to release such trips as and for the purpose specified.

12. The combination with a rotatably mounted hollow shaft and potential energy storing means on said shaft, of a plurality of bearing blocks fixed on the shaft at suitable locations throughout the length thereof, a controlling arm pivotally secured to each bearing block, a plurality of controlling levers pivotally secured to one end of the shaft, wires connecting each lever with a controlling arm and means normally retaining the controlling arms in a position

radiating from the shaft, as and for the purpose specified.

13. The combination with a rotatably mounted hollow shaft and potential energy storing means on said shaft, of a plurality of bearing blocks secured to the shaft at suitable locations throughout the length thereof, a controlling arm pivotally secured to each block and provided with a projecting lip engageable with the block and designed to prevent the controlling arm from being swung outwardly from the shaft farther than the upright position, a collar permanently secured to one end of the shaft and provided with a plurality of extending lugs, controlling levers pivotally secured to the lugs, wires located within the hollow center of the shaft, the ends of the wires protruding through the shaft and being secured respectively to the controlling arms and to the levers and spiral springs engaging with the shaft and with the respective controlling arms, the said springs being mounted on the protruding ends of the wires which connect with the arms, and trips engaging said potential energy storing means to prevent the rotation thereof, said controlling arms being adapted to release such trips as and for the purpose specified.

Signed at Winnipeg this 10th day of February, 1913.

JOSEPH YANCEY CLARK.
